US0D1020099S

(12) United States Design Patent (10) Patent No.: US D1,020,099 S
Yi et al. (45) Date of Patent: * Mar. 26, 2024

(54) NAIL MANICURE MACHINE

(71) Applicant: SHENZHEN GUOYUCHEN TECHNOLOGY CO., LTD., Shenzhen (CN)

(72) Inventors: Shenhui Yi, Shenzhen (CN); Liang Jiang, Shenzhen (CN)

(73) Assignee: SHENZHEN GUOYUCHEN TECHNOLOGY CO., LTD., Shenzhen (CN)

() Term: 15 Years

(21) Appl. No.: 29/770,590

(22) Filed: Feb. 13, 2021

(30) Foreign Application Priority Data

Jan. 18, 2021 (CN) 202130033199.9

(51) LOC (14) Cl. 28-03

(57) CLAIM

The ornamental design for a nail manicure machine, as shown and described.

DESCRIPTION

FIG. 1 is a front elevational view of a nail manicure machine showing our new design;

FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a first perspective view thereof shown; and,
FIG. 8 is a second perspective view thereof shown.
The broken lines shown in the drawings represent environment and form no part of the claimed design.

1 Claim, 6 Drawing Sheets
